(57) **CLAIM**

The ornamental design for an integrated light emitting diode (LED) pendant lamp, as shown and described.

DESCRIPTION

FIG. 1 is a front elevation view of an integrated light emitting diode (LED) pendant lamp showing the new design;

FIG. 2 is a rear elevation view thereof;

FIG. 3 is a left side elevation view thereof, the right side being a mirror image;

FIG. 4 is a top plan view thereof;

FIG. 5 is a bottom plan view thereof;

FIG. 6 is a perspective view thereof;

FIG. 7 is an enlarged top plan view thereof; and,

FIG. 8 is an enlarged bottom plan view thereof.

1 Claim, 8 Drawing Sheets
